COMBINATION FUEL BURNER

Thomas F. Sullivan, Chicago, Ill., assignor to The Babcock & Wilcox Company, Newark, N. J., a corporation of New Jersey

Application January 28, 1936, Serial No. 61,139

17 Claims. (Cl. 158—12)

My present invention relates in general to fuel burners adapted for efficiently burning a plurality of different fluid fuels, either separately or simultaneously.

5 The general object of my invention is the provision of an improved fuel burner construction of the type described, and more particularly a combination fuel burner adapted for installation in a furnace wall having a row of cooling fluid tubes associated therewith. A further and more specific object is the provision in a combination fuel burner for pulverized and gaseous fuels and embodying fuel dispersal devices for the pulverized fuel, of improved means for supplying the 10 gaseous fuel.

15 The various features of novelty which characterize my invention are pointed out with particularity in the claims annexed to and forming a part of this specification. For a better understanding of the invention, its operating advantages and specific objects attained by its use, reference should be had to the accompanying drawing and descriptive matter in which I have illustrated and described preferred embodiments 20 of my invention.

Of the drawing:

Fig. 1 is a vertical section through a tube cooled furnace arch in which is installed a combination fuel burner constructed in accordance with 25 my invention;

Fig. 2 is a section taken on the line 2—2 of Fig. 1;

Fig. 3 is an enlarged sectional view of one of the 30 gaseous fuel discharge members and fuel supply connection thereto; and

Fig. 4 is a view similar to Fig. 2 of a half section of a modified burner construction.

In Figs. 1-3 is shown one embodiment of my improved combination fuel burner arranged to 40 discharge downwardly through a horizontally extending tube cooled furnace wall, such as the arch of a steam boiler furnace. As shown, the arch includes a row of transversely spaced tubes 10 in the boiler circulation system with the intertube spaces closed by blocks 11. Some of the blocks are omitted to form a rectangular port 12 in the arch and across which the tubes 10 extend in spaced relation, and through which the fuel and combustion air are downwardly discharged into the furnace.

The combination fuel burner comprises parts for discharging a pulverized solid fuel, such as pulverized coal, and other parts for discharging a fluid fuel, such as natural gas. The pulverized fuel burner parts consist of a tip member 15

downwardly diverging in two directions and divided into a series of discharge nozzles 16. The nozzle-forming parts are proportioned and arranged to provide a substantially uniform distribution of the fuel to the several nozzles, each of which terminates in a substantially rectangular discharge opening at the outer side of and spaced from a corresponding tube 12. As installed, each nozzle is preferably directly above a corresponding tube and the longitudinal axis of the nozzle 10 discharge opening coplanar with the axis of the corresponding tube, so that the discharge from each pulverized fuel nozzle would impinge upon the outer side of the corresponding tube 10 and be divided thereby into two streams entering the 15 furnace through the intertube spaces at the opposite sides of the corresponding tube. The tubes would thus act as fuel dispersal devices for the corresponding pulverized fuel nozzles, while at the same time protecting the nozzles from over-heating in view of their absorption of a substantial portion of the heat radiated from the furnace through the burner port.

The described pulverized fuel discharge parts 20 described are enclosed by a casing 20 which extends outwardly from the boundaries of the fuel burner port and is connected to any suitable combustion air supply system, so that combustion air will flow not only around the ends of the pulverized fuel burner but also through the channels 30 21 formed between the pulverized fuel discharge nozzles, and then through the intertube spaces therebelow.

To avoid the excessive wear which would occur 35 on the burner port tube portions due to the impingement of the pulverized fuel, these tube portions are provided at their outer sides with fuel dispersal members 22 of any suitable heat and wear-resistant material. Each of the members 22 has its inner side shaped to fit the outer side 40 of the corresponding tube 10 and its outer portion symmetrically tapered outwardly and rounded to provide a substantially equal division of the pulverized fuel stream impinging thereon.

According to my invention alternate fuel dispersal members are employed as fluid fuel discharge manifolds. For this purpose such alternate members 22' are made hollow and substantially crescent-shaped in cross-section with their horn portions terminating at about the center 45 line of the tube row and provided with one or more rows of small discharge openings or orifices 23 in the tips thereof, as shown in detail in Fig. 3. At one end of each member 22' is connected a nipple 24 leading to a corresponding header 25 50

- located in the inner ends of alternate air passages 21 and extending parallel to the corresponding member 22'. The opposite ends of the headers 25 are connected to a tapering supply duct 26 arranged within the air casing 20 and externally connected by a pipe 27 to a suitable source of gaseous fuel. The fuel dispersal parts 22 and 22' are supported on and held in thermal contact with the corresponding wall tubes. The pulverized fuel burner tip member 15 is supported at adjustable distances from the parts 22 and 22' by lugs 28 on the nipples 24 and brackets 29 on the tip member connected by set screws 30, as shown most clearly in Fig. 3.
- With the fuel burner constructed and arranged as described and employed for the separate or simultaneous use of pulverized coal and natural gas, for example, the pulverized coal and primary air will be discharged in elongated streams against the corresponding fuel dispersal devices which divide each stream into two parts entering the furnace through the adjacent intertube spaces. The division of the fuel streams and the deflection of each part into an adjacent secondary air flow path insures an intimate and rapid mixing of the fuel with the air required for combustion before entering the furnace, so that effective short flame combustion is insured. When natural gas is to be burned along with the pulverized coal, the jets of gas are discharged into the issuing streams of pulverized coal and air and rapidly mix therewith adjacent the furnace wall, promoting the combustion of the coal particles. When gas alone is burned, the gas jets mix with the streams of secondary air passing through the corresponding intertube spaces. In either case, the use of a multiplicity of small gas jets will promote the mixing action and insure the desired type of combustion.
- In the modified burner construction shown in Fig. 4, the pulverized fuel burner nozzle tip member 15 is divided into a lesser number of widely spaced nozzles 40, which terminate in elongated rectangular discharge openings at the outer side of and spaced from tube protectors forming the gaseous fuel manifolds 22', which are mounted on alternate wall tubes 10 and constructed and arranged as previously described. With the fuel burner nozzles directed only against tube protectors on alternate tubes, the divided pulverized fuel streams from the nozzles will enter the furnace through separate intertube spaces. Tube protectors 41 are installed on the wall tubes intermediate the gas manifolds 22'. The tube protectors 41 are hollow, each having a concave inner plate 42 fitting against the outer side of the corresponding tube, and a hyperbolic outer plate 43 extending into the space between adjacent fuel nozzles 40 and its sides substantially parallel to the adjacent nozzle sides. This arrangement provides a directional discharge of secondary air through the burner port and also a uniform increase in velocity down to the burner intertube spaces. The plates 42 and 43 are tack welded together and to the corresponding tubes. The tube protectors 41 are filled with suitable heat insulating material 44, such as asbestos, to maintain a temperature on the plates 43 lower than the wall temperature of the tubes 10. The gas manifolds 22' have provisions for air venting and thereby cooling of the same during pulverized fuel or idle burner operation. The lowered temperature in the spaces between and at the outer sides of the wall tubes resulting from this

arrangement eliminates coking and ignition of the pulverized fuel in these spaces.

While in accordance with the provisions of the statutes I have illustrated and described herein the best forms of my invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. A fuel burner comprising a longitudinally elongated fuel discharge nozzle, an elongated fuel dispersal device arranged to receive the impact of the fuel discharged from said nozzle, said fuel dispersal device being hollow and having fuel supply and a multiplicity of small fuel discharge openings therein.

2. A combination fuel burner comprising a plurality of transversely spaced elongated pulverized fuel discharge nozzles, transversely spaced longitudinally elongated fuel dispersal devices arranged to receive the impact of the pulverized fuel discharged from corresponding nozzles, said fuel dispersal devices being hollow and having a multiplicity of small fuel discharge openings therein, and means for supplying gaseous fuel to said hollow fuel dispersal devices.

3. In a furnace wall having a fuel burner port formed therein, a fuel burner arranged to discharge fuel through said burner port comprising a longitudinally elongated fuel discharge nozzle, an air supply casing surrounding said nozzle and opening to said burner port, an elongated fuel dispersal device extending across said burner port and arranged to receive the impact of the fuel discharged from said nozzle, said fuel dispersal device being hollow and having fuel supply and a multiplicity of small fuel discharge openings therein.

4. In a furnace wall having a fuel burner port formed therein, a combination fuel burner arranged to discharge fuel through said burner port comprising a plurality of transversely spaced longitudinally elongated pulverized fuel discharge nozzles, an air supply casing surrounding said nozzles and opening to said burner port, transversely spaced elongated fuel dispersal devices extending across said burner port and arranged to receive the impact of the pulverized fuel discharged from corresponding nozzles, said fuel dispersal devices being hollow and having fuel supply and a multiplicity of small fuel discharge openings therein.

5. In a furnace wall having a fuel burner port formed therein, a combination fuel burner arranged to discharge fuel through said burner port comprising a plurality of transversely spaced pulverized fuel discharge nozzles, an air supply casing surrounding said nozzles and opening to said burner port, transversely spaced fuel dispersal devices extending across said burner port and arranged to receive the impact of the pulverized fuel discharged from corresponding nozzles, said fuel dispersal devices being hollow and having a multiplicity of small fuel discharge openings therein, and gaseous fuel conduits positioned between said nozzles and connected to said hollow fuel dispersal devices.

6. In a furnace wall having a fuel burner port formed therein and a cooling fluid tube extending across said burner port, a fuel burner arranged to discharge fuel through said burner port comprising

- ing a fuel discharge nozzle terminating at the outer side of and with its axis of discharge intersecting the axis of said tubes, an air supply casing surrounding said nozzle and communicating with said burner port, a tube protector extending along the outer side of said tube and arranged to receive the impact of the fuel discharged from said nozzle, said protector being hollow and having fuel supply and discharge openings therein.

5 7. In a furnace wall having a fuel burner port formed therein and a cooling fluid tube extending across said burner port, a combination fuel burner arranged to discharge fuel through said burner port comprising a pulverized fuel discharge nozzle terminating at the outer side of and with its axis of discharge intersecting the axis of said tube, an air supply casing surrounding said nozzle and communicating with said burner port, a tube protector extending along the outer side 10 of said tube and arranged to receive the impact of the pulverized fuel discharged from said nozzle, said protector being hollow and having fuel discharge openings at opposite sides of said tube, and means for supplying gaseous fuel to said hollow tube protector.

15 8. In a furnace wall having a fuel burner port formed therein and a cooling fluid tube extending across said burner port, a combination fuel burner arranged to discharge fuel through said burner port comprising a pulverized fuel discharge nozzle terminating in an elongated discharge opening at the outer side of and with its longitudinal axis coplanar with the axis of said tube, an air supply casing surrounding said nozzle and communicating with said burner port, a tube protector extending along the outer side of said tube and arranged to receive the impact of the pulverized fuel discharged from said nozzle, said protector being hollow and having fuel discharge openings 20 at opposite sides of said tube, and means for supplying gaseous fuel to said hollow tube protector.

25 9. In a furnace wall having a fuel burner port formed therein and a series of transversely spaced cooling tubes extending across said burner port, a combination fuel burner arranged to discharge fuel through said burner port comprising a plurality of transversely spaced pulverized fuel discharge nozzles terminating at the outer side of and with their axes of discharge intersecting the longitudinal axes of corresponding tubes, tube 30 protectors at the outer side of said tubes and arranged to receive the impact of the pulverized fuel discharged from corresponding nozzles, said tube protectors being hollow and having fuel discharge openings 35 at opposite sides of said tubes, and means for supplying gaseous fuel to said hollow tube protector.

40 10. In a furnace wall having a fuel burner port formed therein and a series of transversely spaced cooling fluid tubes extending across said burner port, a combination fuel burner arranged to discharge fuel through said burner port comprising a plurality of transversely spaced pulverized fuel discharge nozzles terminating at the outer side of and with their axes of discharge intersecting the longitudinal axes of corresponding tubes, an air supply casing surrounding said nozzles and communicating with the spaces between said tubes, tube protectors at the outer side 45 of said tubes and arranged to receive the impact of the pulverized fuel discharged from corresponding nozzles, said tube protectors being hollow and having fuel discharge openings 50 at opposite sides of the corresponding tubes, and means for supplying gaseous fuel to said hollow tube protectors.

55 11. In a furnace wall having a fuel burner port formed therein and a series of transversely spaced tubes extending across said burner port, a combination fuel burner arranged to discharge fuel through said burner port comprising a plurality of transversely spaced pulverized fuel discharge nozzles terminating in elongated discharge openings at the outer side of and with their longitudinal axes coplanar with the axes of corresponding tubes, an air supply casing surrounding said nozzles and communicating with the spaces between said tubes, tube protectors extending along the outer sides of said tubes and arranged to receive the impact of the pulverized fuel discharged from corresponding nozzles, said tube protectors being hollow and having fuel discharge openings 60 at opposite sides of the corresponding tubes, and means for supplying gaseous fuel to said hollow tube protectors.

65 12. In a furnace wall having a fuel burner port formed therein and a series of transversely spaced wall cooling tubes extending across said burner port, a combination fuel burner arranged to discharge fuel downwardly through said burner port comprising a diverging pulverized fuel nozzle member divided into a plurality of transversely spaced fuel discharge nozzles terminating in elongated discharge openings at the outer side of and with their longitudinal axes coplanar with the axes of corresponding tubes, an air supply casing 70 surrounding said nozzles and communicating with the spaces between said tubes, tube protectors extending along the outer side of said tubes and arranged to receive the impact of the pulverized fuel discharged from corresponding nozzles, alternate tube protectors being hollow and having fuel discharge openings at opposite sides of the corresponding tubes, and gaseous fuel conduits positioned between said nozzles and connected to said hollow tube protectors.

75 13. In a furnace wall having a fuel burner port formed therein and a series of transversely spaced wall cooling tubes extending across said burner port, a gaseous fuel burner arranged to discharge fuel through said burner port comprising a plurality of transversely spaced hollow metallic fuel discharge members extending along the outer side of and separate from corresponding tubes and each of said fuel discharge members having portions terminating at opposite sides of said corresponding tubes, and a series of small fuel discharge openings in the inner ends of said portions.

80 14. In a furnace wall having a fuel burner port formed therein and a series of transversely spaced wall cooling tubes extending across said burner port, a gaseous fuel burner arranged to discharge fuel through said burner port comprising a plurality of transversely spaced hollow metallic fuel discharge members extending along the outer side of and separate from corresponding tubes and each of said fuel discharge members having portions terminating at opposite sides of said corresponding tubes, a series of small fuel discharge openings in the inner ends of said portions, an air supply casing surrounding said fuel burner and opening to said burner port, and gaseous fuel conduits connected to said discharge members.

85 15. In a furnace wall having a fuel burner port formed therein and a series of transversely spaced wall cooling tubes extending across said burner port, a gaseous fuel burner arranged to discharge fuel downwardly through said burner port comprising a plurality of transversely spaced crescent-shaped hollow fuel discharge members ex-

tending along the outer side of and separate from corresponding tubes and each of said fuel discharge members having portions terminating at opposite sides of said corresponding tubes, fuel discharge openings in the inner ends of said portions, an air supply casing surrounding said fuel burner and opening to said burner port, a fuel supply header in said air casing extending transversely of said discharge members, and gaseous fuel conduits connecting said header to said discharge members.

16. In a furnace wall having a fuel burner port formed therein and a series of transversely spaced tubes extending across said burner port, a combination fuel burner arranged to discharge fuel through said burner port comprising a plurality of transversely spaced pulverized fuel discharge nozzles terminating at the outer side of and with their axes of discharge intersecting the longitudinal axes of corresponding alternate tubes, an air supply casing surrounding said nozzles and communicating with the spaces between said tubes, tube protectors at the outer side of said alternate tubes and arranged to receive the impact of the pulverized fuel discharged from corresponding nozzles, said tube protectors being hollow and having discharge openings at op-

posite sides of the corresponding tubes, and means for supplying gaseous fuel to said hollow tube protectors.

17. In a furnace wall having a fuel burner port formed therein and a series of transversely spaced tubes extending across said burner port, a combination fuel burner arranged to discharge fuel through said burner port comprising a plurality of transversely spaced pulverized fuel discharge nozzles terminating at the outer side of and with their axes of discharge intersecting the longitudinal axes of corresponding alternate tubes, an air supply casing surrounding said nozzles and communicating with the spaces between said tubes, tube protectors at the outer side of said alternate tubes and arranged to receive the impact of the pulverized fuel discharged from corresponding nozzles, hollow tube protectors at the outer side of the tubes intermediate said alternate tubes, said last mentioned tube protectors extending outwardly beyond said first mentioned tube protectors and having their sides parallel to the sides of the adjacent fuel nozzles, and heat insulating material filling said hollow tube protectors.

THOMAS F. SULLIVAN.
